GAME APPARATUS

Edward W. Willig, Cincinnati, Ohio

Application September 26, 1940, Serial No. 353,501

11 Claims. (Cl. 273—138)

This invention relates to a game apparatus in which a number of people may take part.

An object of the invention is to provide a table-like structure formed in its top portions with movable sections adapted to be actuated by an operator to an inwardly inclined or tilted position, means likewise being provided for retaining an undetermined one of the movable sections in its normal horizontal position.

Another object is the provision in a game of this character, of simple and efficient mechanisms for effecting the movements and results referred to.

Another object is to provide a game of this kind in which the players may be supplied, before a play, with suitable playing pieces adapted to be placed on the movable sections above referred to, the invention likewise providing novel means for collecting and concentrating at one point the playing pieces utilized.

Another object is to provide, an apparatus of the nature described, means for facilitating the various mechanical movements involved so that the game may be played without delay or undue effort on the part of the operator.

These and other objects are attained by the means described herein and illustrated in the accompanying drawings, in which:

Fig. 1 is a top plan view of the game apparatus of this invention.

Fig. 2 is a side elevational view of the same.

Fig. 3 is an enlarged cross-sectional view on the line 3—3 of Fig. 1.

Fig. 4 is a view, partly in cross-section, on the line 4—4 of Fig. 2.

Fig. 5 is a cross-sectional view on line 5—5 of Fig. 1.

Fig. 6 is a cross-sectional view on line 6—6 of Fig. 2.

Fig. 7 is a cross-sectional view on line 7—7 of Fig. 3.

Fig. 8 is a fragmental cross-sectional view of two adjacent trays forming part of the apparatus.

Fig. 9 is a detail view of the retaining arm forming part of the apparatus shown in position on its supporting shaft, the latter being shown in cross-section.

Fig. 10 is a cross-sectional view on line 10—10 of Fig. 9.

Fig. 11 is a view similar to Fig. 2, with parts omitted, showing the movable portions of the apparatus in lowered or deposit position.

The apparatus may comprise a horizontal frame 15 which may be of octagonal outline and

formed of peripheral members 16 and radial members 17, said members providing generally triangular spaces therebetween, in each of which one of the trays to be later described, is positioned. The radial members 17, as herein shown, are each formed of two strips of wood laid side by side.

The octagonal frame 15 may be supported by legs 18 mounted upon a cruciform base 19. Auxiliary vertical supports 20 may likewise be provided if desired.

Trays 21 are mounted in the triangular openings formed in the horizontal frame 15, as shown in Figs. 1, 5 and 7. The trays, as seen in Fig. 5, are preferably formed with an upstanding rear rim 22 and lateral rims 23. The latter terminate short of the inner end of the tray and the inner ends of the trays, as seen especially in Fig. 7, are cut off or truncated and are overlapped by a central covering member 24, (Fig. 1). The outer ends of the trays are hingedly connected as at 25, (Fig. 5), to the peripheral frame members 16, which hinges form the only connection of the trays to the frame so that the trays are adapted to be swung downwardly and inwardly of the frame in the playing of the game. In order to prevent the player's fingers, or other objects from being caught between the frame members 16 and the rear rims 22 of the trays, the overlapping guard strips 26 (Fig. 5), may be attached to the upper surface of the members 16.

The trays are held in their normal horizontal position by means of an annular frame-like support 27 (Fig. 3), comprising a ring 28 which extends beneath the trays. To the ring 28 oppositely disposed angle brackets 29 are secured, as at 30, for supporting a cross-frame 31 attached as at 32 to said brackets.

The center of the cross-frame 31 is apertured as at 33 for slidably embracing a central hollow standard 34, (Fig. 3). A solid and rigid positioning of this standard may be achieved by providing a basal sleeve 35 within which the lower end of the standard 34 is firmly set and supported, as upon an internal shoulder 36 formed in the sleeve 35. The lower end of the said sleeve may be flanged as at 37 and secured to the members 19 of the base. For further rigidifying the supporting sleeve 35, a support shelf 38, closely embracing the sleeve 35 is provided. The shelf member 38 is supported by brackets 39 secured as at 40 to the under-side of said shelf and at 41 to the base 19.

The tray support described as slidably mounted on the standard 34 is adapted to be vertically

actuated thereon by an operator, through the medium, as herein shown, of a leverage system. For this purpose there may be provided a fulcrum rod 42 having its ends supported by a pair of arms 43 attached to and projecting from two oppositely disposed legs 18. The fulcrum rod 42, as seen in Fig. 6, passes, adjacent its middle, through a T connection 44 and this in turn is supported by a horizontal brace 45, attached by vertical connections 46, (Fig. 2), to the base 19. The brace 45 may be additionally strengthened by a depending support 47 secured as at 48 to the under-side of the horizontal frame 15.

The fulcrum rod 42 has rotatably mounted thereon a fulcrum connection 49 (Fig. 3), formed with angular extensions 50 and 51. The lower extension 50 has the inner end of a link 52 (Figs. 2 and 6) pivotally connected therewith as at 53. The opposite end of link 52 is pivotally connected as at 54 with an upright lever 55 which, at its lower end, is hingedly connected with the base 19 as at 56, (Figs. 2 and 4). The lever 55, as seen in Figs. 1 and 2, projects through one of the radial members 17 of the frame 15 through a slot 57 formed in the latter, the lever, at a point below the frame 15 being preferably bent toward the center of the frame 15.

The extension 51 of the fulcrum member 49 has projecting therefrom a stub shaft 58 (Figs. 3 and 6), to which is rigidly secured, by means of a T connection 59, a bar 60, to each end of which a shoe member 61 is secured by use of a suitable connection 62. Shoe member 61 bears continuously against the lower surface of a U-shaped bracket 63, (Figs. 2, 4, and 6), said brackets being secured, in depending relation, to a cross-beam 31 of the tray support.

When the lever 55 is pushed inwardly of the table, as seen in Fig. 2, the shoe members 61, bearing against the U-brackets 63, carry the tray support 27 upwardly whereby the trays are all held in horizontal position, supported on the top edge of the ring member 28 of the tray support. When the lever 55 is moved outwardly in the slot 57, the shoe members 61 are actuated in a downward arc by the leverage mechanism described, and the tray support is thereby lowered, the trays at this time being tilted downwardly and inwardly of the table as shown in Fig. 11.

The vertical movement of the tray support may be guided and stabilized by means of vertical rods 64 (Figs. 2, 3, 4, and 5), fixed between the top and bottom portions of the table and slidably embraced, in their upper portions, by metal rings 65 secured to the top and bottom portions of the tray support. A level terminal position for the tray support may be assured by the use of a stop 66 secured on each of the rods 64 at the desired height.

Up and down movement of the tray support may be facilitated by the use of counterweights. In Fig. 4 a cable 67 is shown, having one end attached to the tray support as at 68 and the other end, after passing over a pulley 69, connected with a counterweight 70, as at 71. The counterweighting means may be provided at several points around the circumference of the tray support, as desired.

In Fig. 1, means are shown for holding the lever 55 in its normal inward position. These means may comprise a stop block 72 hingedly connected, along its rear edge 73, to the radial member 17 in which the lever slot 57 is formed. In its lowered position the stop block overhangs the slot 57 and the inner end of the block is contacted by the le-

ver 55 which is thereby prevented from moving outwardly in the slot 57. When the lever block 72 is raised, the slot 57 is left clear for outward movement of the lever therein.

5 In the playing of the game involving the present apparatus, an undetermined one of the tray members, upon tilting of the trays, is maintained in its horizontal position. Thus for example, the various players, prior to the start of the game 10 may each be supplied with an equal number of small discs or other playing pieces. Each player selects the tray upon which he places one of his playing pieces. Thereafter, when the trays are actuated, the player who has selected the tray which remains horizontal is considered winner of that play, and receives back his own playing piece and a certain number of additional pieces contributed either by the other players or by a selected one of them serving as "banker" in accordance with a system of "odds" which system, in its mechanical details will be later described.

For retaining an undetermined one of the tray members in horizontal position, upon downward actuation of the tray support, there is provided 15 in accordance with this invention, vertical shaft 74 (Fig. 3) projecting downwardly into the central standard 34, and supported therein by means of a stop 75 fixed to the shaft and resting, preferably, upon ball-bearings at 76 supported in a cup member 77 secured within the hollow standard 34. A proper and non-frictional positioning of the shaft 74 may likewise involve the use of a set of ball-bearings 78 suitably associated with the interior of the standard 34, adjacent the 20 lower end thereof, and another set of ball-bearings 79 positioned within a hub 80 disposed on the top central surface of the frame 15.

The means for holding up an undetermined one of the trays in the playing of the game, may 25 comprise a retaining arm 81 (Figs. 3, 7, 9, and 10) fixed in and projecting laterally from an annular block 82 loosely embracing the shaft 74, beneath the top portion of the table, and resting upon an annular centrally apertured disc 83. 30 This latter, in turn, rests upon the top edge of the hollow standard 34. The block 82 is formed with an interior annular chamber 84 for accommodating a smaller annular block member 85 secured to the shaft 74 by a set screw 86. The 35 larger block 82, (Fig. 9), is cut with a lateral segmental aperture 87 into which projects a stub arm 88 projecting from and fixed in the small block 85. The purpose of this specific structure will be further explained.

50 At the top of the central shaft 74 a fly-wheel 89 may be secured between a stop 91 and a nut member 92 positioned on the threaded upper end of shaft 74. The wheel serves as a suitable means for rotating the shaft 74 and at the same 55 time weights down the shaft to insure its smooth non-vibratory motion. The fly-wheel 89 may be provided with projecting handles 90 to be grasped in giving movement to the wheel.

It will be apparent that the tray-retaining arm 60 81 will be rotated with the shaft 74 by virtue of the stub arm 88 which contacts one of the ends of the segmental opening 87 provided in the larger block 82. In order to render the position of the arm 81 beneath the table top entirely undeterminable, the additional means shown and described in connection with Figs. 9 and 10, are provided. Thus, after the shaft 74 has stopped rotating, the larger block 82, as the result of inertia, will rotate in the opposite direction until the stub arm 88 reaches the opposite side of a

segmental opening 87 and the retaining arm is similarly carried around.

Now, when the lever 55 is moved outwardly in its slot for lowering the trays, the arm 81 will be disposed beneath one of the trays and preclude its being tilted downwardly.

In order to assure that the retaining arm will not come to rest between the lateral edges of two adjacent trays, and thereby be rendered inoperative, the inner ends of the bottoms of the trays may have secured thereto an extension strip 93, (Figs. 7 and 8), the ends of which project on both sides of the associated tray. In addition, one end of this strip may have fixed thereto, as seen especially in Fig. 8, a down-bent stop finger 94, the outer and lowermost end of which is slightly above the annular path of the rotating retaining arm 81. If the latter should stop just beneath the said outer end of the finger 94, the arm would be actuated toward the center of the associated tray. The opposite end of the extension strip 93 is of sufficient strength to hold up the tray should the retaining finger 81 come to rest beneath said end.

As already stated, it is desirable to provide "odds" in the playing of the game. For this purpose, as seen in Fig. 3, the top portions of the shaft 74 below the fly-wheel 89, may have mounted thereon a rotatable disc 95, preferably provided with ball-bearings 96 and resting upon a block 97 fixed as at 98 to the shaft 74. If desired, the disc 95 may be constructed on the underside with an annular flange 99 loosely embracing the block 97.

Laterally projecting rods 100, equal in number to the number of trays and similarly spaced apart, are connected to the disc 95. For carrying out the idea that the trays constitute various kinds of pieces of pie, the outer ends of the rods 100 may have pivotally connected therewith the knives 101 bearing plates 102 upon which the "odds" are indicated as seen in Fig. 2. The disc 95 is adapted to be rotated at the same time as the fly-wheel 89, and in fact, may automatically be carried around with the shaft 74 as a result of frictionally contacting therewith. The radial member 17 of the table, in the pathway of the rotating knives, may each have connected thereto an upstanding lug 103, against which the lower tips of the knives come into contact during rotation, for giving a clicking sound to add interest to the game, and likewise, when the knives come to rest adjacent the lugs 103 and gently bump thereagainst, to cause the knives to move back toward a position above the center of the trays. The knife stopping above the horizontally maintained tray, after a play, indicates the "odds" which the winner is to receive from the other players or from the "banker."

The tray support may carry a fabric receptacle 104 (Figs. 2, 3, and 4), into which the playing pieces are deposited when the trays are tilted. Receptacle 104 is apertured and the bottom thereof suitably inclined in the vicinity of these apertures whereby the playing pieces are delivered to an upper slide 105 positioned beneath the tray support and connected with the latter, at the upper end, as by a length of chain 106 (Fig. 3.) The slide 105 is centrally apertured to receive the basal sleeve 35 and the forward or lower end of the slide rests upon a suitable support member 107. The lower end of the slide empties into an auxiliary slide plate 108, the upper end of which may be attached to the support sleeve, as at 109, and the lower end of which projects

5 into a box 110 suitably positioned on the base 19 of the table. Obviously, the playing pieces received from the receptacle 104 on the tray support, pass downwardly of the slide 105, onto the slide of plate 108, and thence into the box 110.

Modifications will suggest themselves upon disclosure of the means herein, but these are believed to be comprised within the spirit and scope of the invention.

What is claimed is:

1. A game apparatus comprising a horizontal frame, play elements hingedly mounted on the frame, means for simultaneously moving said elements from normal horizontal positions to inwardly inclined positions and return, and means holding up an undetermined one of said play elements while the remainder are lowered.

2. A game apparatus comprising a horizontal frame, radially disposed trays associated with the frame and having their outer ends hingedly connected therewith, means for simultaneously moving the trays on their hinged mountings from horizontal to inwardly inclined positions and return, and means for holding up an undetermined one of said trays while the remaining trays are lowered.

3. A game apparatus comprising a horizontal frame, play elements hingedly mounted on the frame, means for simultaneously moving said elements from normal horizontal positions to inwardly inclined positions and return, and means adapted to be actuated prior to movement of the play elements for holding up an undetermined one of said elements while the remainder are lowered.

4. A game apparatus comprising a horizontal frame, play elements hingedly mounted on the frame, a support member associated with the play elements and normally holding the latter in horizontal receiving position, means for moving the support member to effect simultaneous inclination of the play elements into deposit position and to return said elements to horizontal position, and means adapted to be actuated prior to tilting of the play elements for holding in horizontal position an undetermined one of said elements while the remainder are tilted.

5. A game apparatus comprising a horizontal frame, a number of play elements hingedly mounted on the frame, means for simultaneously moving said elements from normal horizontal positions to inclined positions and back, and a freely movable retaining member associated with the play elements and adapted to be actuated prior to movement of the play elements and to preclude movement of a previously undetermined one of said play elements to inclined position, upon actuation of the remaining play elements to such position.

6. A game apparatus comprising a horizontal frame, play elements hingedly mounted on the frame, a support member associated with the play elements and normally holding the latter in horizontal receiving position, means for moving the support member to effect simultaneous inclination of the play elements into deposit position and to return said elements to horizontal position, and a freely movable retaining member associated with the play elements and adapted to be actuated prior to movement of the play elements and to preclude movement of a previously undetermined one of said play elements to inclined position upon actuation of the remaining play elements to such position.

7. A game apparatus comprising a horizontal

frame and supports therefor, a number of relatively elongated trays radially disposed and having their outer ends hingedly connected to the frame, a tray support mounted for vertical slideable movement beneath the frame, means for actuating the tray support to effect hinged movement of the trays from normal horizontal positions to inwardly-inclined deposit positions and return, and means adapted to be actuated prior to tilting of the trays for retaining in horizontal position an undetermined one of the trays while the other trays are actuated to inclined position.

8. A game apparatus comprising a horizontal frame and supports therefor, a number of relatively elongated trays radially disposed and having their outer ends hingedly connected to the frame, a tray support mounted for vertical slideable movement beneath the frame, means for actuating the tray support to effect hinged movement of the trays from normal horizontal positions to inwardly-inclined deposit positions and return, and a freely movable retaining member positioned beneath the trays and adapted to be actuated prior to movement of the trays and to preclude tilting of an undetermined one of the trays when the other trays are actuated to inclined position.

9. A game apparatus comprising a horizontal frame, radially disposed trays associated with the frame and having their outer ends hingedly connected therewith, means for simultaneously moving the trays on their hinged mountings from horizontal to inwardly inclined positions and return, means for holding up an undeter-

mined one of said trays while the remaining trays are lowered, and means for receiving from the tilted trays articles deposited thereon while the trays are in horizontal position.

10. A game apparatus comprising a horizontal frame, radially disposed trays associated with the frame and having their outer ends hingedly connected therewith, means for simultaneously moving the trays on their hinged mountings from horizontal to inwardly inclined positions and return, an arm radially mounted beneath the trays for free circular movement and adapted to be actuated prior to movement of the trays to inclined position and to come to rest beneath an undetermined one of said trays to preclude tilting thereof when the other trays are moved to inclined position.

11. A game apparatus comprising a horizontal frame and supports therefor, a number of relatively elongated trays radially disposed and having their outer ends hingedly connected to the frame, a tray support mounted for vertical slideable movement beneath the frame, a lever system associated with the tray support and adapted to be actuated adjacent the periphery of said horizontal frame for effecting hinged movement of the trays from normal horizontal positions to inwardly-inclined deposit positions and return, and means adapted to be actuated prior to tilting of the trays for retaining in horizontal position an undetermined one of the trays while the other trays are actuated to inclined position.

EDWARD W. WILLIG.
